H. T. TUCKER

FOLDING CHAIR

Filed Oct. 21, 1924

UNITED STATES PATENT OFFICE.

HENRY TEMPLE TUCKER, OF FORT SMITH, ARKANSAS.

FOLDING CHAIR.

Application filed October 21, 1924. Serial No. 744,959.

To all whom it may concern:

Be it known that I, HENRY T. TUCKER, a citizen of the United States, residing at Fort Smith, in the county of Sebastian and State of Arkansas, have invented certain new and useful Improvements in a Folding Chair, of which the following is a specification.

This invention relates to improvements in chair constructions.

The primary object of this invention is the provision of a folding chair, which may be folded into a compact flat structure, or extended to provide a stable well balanced chair capable of supporting persons of extreme weight, due to the sturdy and effective manner of securing the parts.

A further object of this invention is the provision of a folding chair, which includes parts which are movably connected by wooden parts, in a novel manner, so as to dispense with castings, and other metal clips and parts which occasionally become loosened, bent, and detached.

A further object of this invention is the provision of a folding chair which may be easily extended or collapsed.

A further object of this invention is the provision of a novel chair structure including a back portion cooperably associated with the seat structure thereof so that the back portion will assume a comfortable rigid position with respect to the seat when the chair is extended and folded into substantial parallelism with the seat when the chair is folded into a flat compact structure.

Other objects and advantages of this invention will be apparent during the course of the following detailed description.

In the accompanying drawing, forming a part of this specification, and wherein similar reference characters designate corresponding parts throughout the several views,

Figure 1 is a cross sectional view taken longitudinally through the chair in its extended relation.

Figure 2 is a similar cross section of the chair parts with the chair in collapsed position.

Figure 3 is a fragmentary view, partly in cross section, of the upper front corner of the chair when the parts thereof are collapsed.

Figure 4 is a rear elevation of the chair in folded position.

In the drawing, wherein for the purpose of illustration is shown a preferred embodiment of this invention the letter A may generally designate the chair which may include a supporting structure B; seat C; and back D.

Referring to the supporting structure B, the same provides a pair of side bars or members 15 and 16, which at their lower portions provide legs 17 and 18 respectively, and at their upper portions provide the back rails 19 and 20 respectively. Front legs 21 and 22 are respectively provided for pivotal connection to the legs 17 and 18 by means of a cross bar 23, so that the legs 21 and 22 are effectively pivoted inwardly of the legs 17 and 18, and whereby when the chair is in position for seating purposes the pivot cross bar 23 will be disposed below the seat C substantially midway of the forward and rearward parts thereof, so that the ends of the front and rear pairs of legs are suitably distanced to properly and stably support the chair.

Inwardly of their facing inside surfaces the back members 19 and 20 are provided with longitudinally extending grooves 24 therein, provided for purpose of guiding the operation of the seat C, as will be described.

Referring more particularly to the seat structure C, the same includes the side rails 30 and 31, with the front and rear main supporting bars 32 and 33 extending between the same and affixed therein in any approved manner. The seat slats 35 are provided in any approved number, at their edge being supported in grooves provided at the inside surfaces of the rails 30 and 31, and preferably assisted in their support by the main front and rear supporting members 32 and 33. This provides a very durable construction.

At its forward end, and preferably below the slat 35 immediately adjacent the supporting bar 32, a pivot brace 38 is provided, extending transversely through the rails or members 30 and 31 of the seat C, and providing projections which are pivoted in the upper ends of the legs 21 and 22, to give the seat C a stable pivot action on the legs 21 and 22.

The seat rails 30 and 31 toward the rear thereof are provided with lateral bearing projections 40 and 41, which at their outer surfaces are in sliding contact with the inside surfaces of the back rails 19 and 20;

these projections 40 and 41 preferably supporting pins 42 which project laterally of their respective projections for slidable disposition in the grooves 24. These pins 42 it should be noted are not at the extreme rear ends of the rails 30 and 31, but permit said rails to project beyond the back rails 19 and 20 when the seat is in horizontal position. For its horizontal resting position the seat 10 is supported by means of the pins 42, which rest in the lower ends of the grooves 24, to properly brace the pairs of front and rear legs to hold the seat in such position.

The back D in addition to the rails 19 and 15 20 above mentioned includes the swinging back portion 45, which consists of the top cross member 47 at its ends being pivoted by spindle extensions 48 in the upper ends of the rails 19 and 20, so that the back portion 20 45 may swing to permit the proper folding and unfolding of the chair. The back portion 45 furthermore includes the vertical slats 49, which at their lower ends are connected by means of a short cross piece 50, 25 which is not connected to any part of the chair, except to the slats 49.

The ends of the seat rails 30 and 31 which extend beyond the back rails 19 and 20, when the seat is in horizontal position, as is 30 illustrated in Figure 4, support a cross bar or piece 53, in spaced relation with the rear-most seat member 33 and the axis of which cross rail 53 is disposed below the plane of the seat formed by the slots 35. The lower 35 swinging end of the back 45 is disposed in this opening 55° between the seat member 33 and the retaining bar 53, to guide the back portion 45 into its folded or unfolded seating relation.

40 At its upper end the chair is preferably provided with a hand grasping cross bar 58, connected in the back rails 19 and 20 at the very upper ends thereof. A cross brace 60 is similarly provided at the lower ends 45 of the rear legs 21 and 22.

From the foregoing description of this invention the operation will be obvious. Assuming the chair to be in seating position, as is illustrated in Figure 1, in order to fold 50 the same it is merely necessary for the operator to grasp the cross piece 58 with his hand, and by placing his foot on the cross rail 60 and pulling upwardly, the seat C will be pivotally swung upon its pivot piece 38, 55 and the pins 42 will slide upwardly in the groove 24, to permit the rear legs; the seat; and the back portion 45 to fold into flat collapsing relation within the area formed by the outer margins of the bars 15 and 16, and 60 as is illustrated in Figure 2 of the drawings. The back portion 45 is guided in its folded or unfolded position by means of the bar 33 and the cross piece 53, and the back is folded in a plane substantially parallel with 65 the seat when the chair is folded, and when

the chair is unfolded the back is slightly tipped rearwardly at its lower end to place the same in proper posture for comfortable seating purposes. It is to be noted that all of the chair parts are formed of wood, even 70 the bearing pins and cross braces. The parts may be made of metal if desired, although the use of clips and metal castings is obviated by the structure shown, thus providing a chair which is relatively simple 75 to construct, economical to manufacture, and which may be easily folded or unfolded. As for the unfolding of the chair it is merely necessary for the operator to grasp the same by the rail 58 at the top of the chair, 80 and by swinging the chair outwardly at its lower end and hitting the lower ends of the rear pair of legs 21 and 22 on a floor surface, with the front of the chair facing the person, the chair will immediately become 85 unfolded.

Various changes in the shape, size, and arrangement of parts may be made to the form of the invention herein shown and described, without departing from the spirit 90 of the invention or the scope of the claims.

I claim:

1. As an article of manufacture a folding chair comprising a pair of main bars each including at its lower portion a front supporting leg and each including at its upper portion a back rail rigid with its respective leg, a pair of rear legs pivotally connected intermediate their ends between the ends of said front legs inwardly of said front legs, a seat pivotally connected at its forward end to the upper ends of said rear legs, means pivotally and slidably connecting the rear portion of said seat to said back rails whereby the rear portion of said seat extends rearwardly of said back rails when the seat is positioned for seating purposes, means providing a transverse opening in said seat at its rear end, and a back pivotally connected at its upper end to the upper ends of said back rails and having its lowest free swinging end slidably disposed through the opening provided at the rear of said seat. 105

2. As an article of manufacture a folding chair comprising a pair of side bars, a pair 115 of rear legs pivotally connected intermediate their ends between the ends of said side bars, a seat member pivotally connected at its forward end to the upper ends of said rear legs, means slidably connecting the rear end of said seat to said side bars and between the same, a cross bar carried by said seat rearwardly thereof and in spaced relation with said seat to provide a transverse opening, and a back member pivotally connected at 120 its upper end to the upper end of said side bars and at its lower swinging end being slidably disposed in the transverse opening above mentioned. 125

3. In a folding chair the combination of 130

a pair of side bars providing a pair of front supporting legs and a pair of back rails, a pair of front supporting legs pivotally connected between their ends between the 5 ends of said front supporting legs, a seat structure pivotally connecting at its forward end to the upper ends of said rear legs and at its rear end being slidably connected to the back rails, said seat including a seat 10 platform and side rails which extend rearwardly of the back rails when the seat is in seating relation, a cross bar carried by said seat side rails at their rear ends and in spaced relation with the platform to provide 15 a transverse slot which is disposed rearwardly of the back rails when the seat platform is in horizontal seating relation, said cross bar being disposed below the plane of said seating platform, and a swinging back 20 pivotally connected at its upper end between the back rails at their upper ends and at its lower end slidably resting within the transverse slot provided between the seat platform and the cross bar supported by 25 said seat side rails.

4. A folding chair comprising collapsible front and rear leg constructions, a back construction including back rails and a back member pivoted at its upper end to said 30 back rails, and a seat structure collapsibly connected with said front and rear leg con-

structions and including side rails and a seating portion, said side rails at their rear ends extending beyond the edge of said seating portion, and a transverse bar connected 35 by said rear ends of said seat side rails below the plane of the seating portion of said seat structure, to provide an opening between the rear edge of said seat portion and said bar through which the lower swinging end of said back member slidably extends to guide and support the back member in extended or collapsed relation to the seat and back rails.

5. A folding chair comprising collapsible 45 front and rear legs constructions, a back construction including back rails, and a back member pivoted at its upper end to said back rails, and a seat structure collapsibly connected with said front and rear leg constructions and at its rear end having a substantially transverse slot-like opening thru which the lower swinging end of the back member slidably extends, said seat structure 50 forwardly and rearwardly of said slot-like opening providing portions for retaining the back member in position to guide and support the said back member in its extended or collapsed relation to the seat and back rails.

HENRY TEMPLE TUCKER.
